UNITED STATES PATENT OFFICE

RICHARD J. NETZEL, OF LAKEWOOD, OHIO, ASSIGNEE TO ADELE MARY ORR, OF CLEVELAND, OHIO, AND THE CLEVELAND TRUST COMPANY, OF CLEVELAND, OHIO, A CORPORATION OF OHIO, EXECUTORS OF WILLIAM ORR, DECEASED

WRINGER

Application filed August 12, 1931. Serial No. 556,537.

My invention relates to machines and apparatus, which may be more particularly adapted for wringing clothes, and which may include two longitudinally extending rolls, releasable means for pressing the rolls against each other, the longitudinal axes of the rolls being preferably parallel, and means for releasing the pressure applying means.

10 In the case of clothes wringers, the rolls are frequently made of rubber and it is desirable to release the pressure of one roller upon the other when the wringer is not in use.

Moreover in the case of power driven 15 wringers, particularly for household use, it is practically essential that means be provided for quickly releasing the pressure between the rolls, and it is desirable that the releasing means may be operated by involuntary 20 action of the user, so that in the event that the user's fingers are caught between the rolls, the pressure between the rolls may be released before serious injury has been inflicted.

25 My invention furthermore relates to the structure and arrangement of the bearings for the wringer rolls, to the power drive for the rolls, to automatically reversing drain boards, and to feed boards for wringers and 30 the like.

The objects of the present improvements include the provision of simple and efficient means for yieldingly pressing wringer rolls and the like against each other combined 35 with positive means substantially instantaneously operative by a single action on the part of the user to release the pressure applying means.

40 Further objects of the improvements include the provision of a simplified and easily manufactured structure and arrangement of the bearings for the wringer rolls and of the power drive for the rolls.

45 Further objects of the improvements include the provision of a wringer having a simplified and effective automatically reversing drain board.

Further objects of the improvements in- 50 clude the provision of a wringer having an

improved and simplified structure and arrangement of the feed boards therefor.

The foregoing and other objects are attained by the wringer, apparatus, parts, improvements and combinations, which comprise the present invention and which are particularly and distinctly pointed out and set forth in the appended claims forming part hereof.

In general terms, the improved wringer of the present invention may be described as including a frame, a normally lower roll and a normally upper roll, means journaling the lower roll in the frame, bearing blocks journaling the upper roll, means mounting the bearing blocks in the frame for sliding towards and away from the lower roll, a head, preferably yielding means located at one side of the rolls and mounting the head for pivoting about a normally horizontal axis, means on the head adapted for abutment against the bearing blocks for the upper roll for pressing the upper roll against the lower roll, hook means, means located on the frame at the other side of the rolls and preferably yieldingly mounting the hook means for pivoting about a normally horizontal axis, shaft means rotatably mounted on the head, hook engaging means mounted on the shaft means for selectively engaging the hook means by rotation of the shaft means for applying pressure to the rolls, means mounted on the shaft means for positively displacing the hook means from the engaging means by further rotation of the shaft means, and a lever for 75 rotating the shaft means.

The improved wringer furthermore includes reversible bearing blocks for the upper roll, one reversible bearing block for one end of the lower roll, and an easily separable bearing and drive connection for the other end of the lower roll.

The improved wringer furthermore includes a drain board pivotally mounted on the frame below the normally lower roll, the lower roll including a shaft, preferably split collar means frictionally mounted on the lower roll shaft, and means providing an operative connection between the frictionally mounted collar means and the drain board 100

for reversing the inclination of the drain-board when the direction of rotation of the rolls is reversed.

The improved wringer furthermore includes a formed metal feed board located at each side of the rolls, and each feed board including a hanger pin extending from each end thereof, and the frame having formed therein preferably upward and oppositely opening slotted shoulders, each shoulder being adapted for removably supporting one of the hanger pins.

A preferred embodiment of the present improvements is illustrated in the accompanying drawings forming part hereof, in which

Figure 1 is a fragmentary front elevation view of a wringer embodying the present improvements, the several parts being illustrated in their normal positions for normal operation of the wringer with the improved head engaged by the hook means and applying pressure between the rolls;

Fig. 2, a fragmentary top plan view thereof;

Fig. 3, a longitudinal vertical sectional view thereof;

Fig. 4, a transverse sectional view thereof as on line 4—4, Figs. 1, 2 and 3;

Fig. 5, a view similar to Fig. 4 illustrating in full lines the several parts of the wringer after the head shaft lever has been operated for releasing the engagement of the hook means with the engaging means, whereby the pressure between the rolls has been released, and illustrating the head in dot-dash lines swung open for removing the upper roll from the frame;

Fig. 6, a view similar to Figs. 4 and 5, in which the several parts are illustrated in their respective positions just before rotation of the head shaft lever for engaging the engaging means with the hook means;

Fig. 7, a transverse sectional view as on line 7—7, Figs. 1, 2, and 3, illustrating the improved drain board and feed board construction and arrangement.

Similar numerals refer to similar parts throughout the several views.

The improved wringer is indicated generally at 10 and includes an improved frame indicated generally at 11, and the improved frame 11 includes a longitudinally extending base member 12 whose upper surface 12' is preferably convex and laterally symmetrical with respect to the normally vertical longitudinal median plane of the wringer, indicated by the dash and double dot line M.

The base 12 is preferably provided with a plurality of reinforcing ribs 13 extending preferably radially from a central intersection 14 on the plane M and downwardly from the lower concave surface 12'' of the base member 12.

The frame 11 furthermore includes housing and supporting members 15a and 15b ex-

tending upwardly respectively from the opposite ends of the base 12.

The housing and supporting member 15a includes longitudinally spaced laterally and vertically extending walls 16a and 17a and laterally spaced longitudinally and vertically extending walls 18a and 19a. The walls 16a and 17a merge at their vertically extending edges with the walls 18a and 19a to form a vertically extending housing chamber 20a which is open at its lower end.

The housing and supporting member 15a also includes an upper normally horizontal wall 21—1a merging at its edges with the upper edges of the walls 16a, 18a, and 17a, and with the upper end of a normally vertical wall 22a extending longitudinally between the walls 16a and 17a, and the wall 22a is laterally spaced from one side of the median plane M.

The housing and supporting member 15a also includes an upper normally horizontal wall 21—2a merging at its edges with the upper edges of the walls 16a, 19a, and 17a, and with the upper end of a normally vertical wall 23a extending longitudinally between the walls 16a and 17a, and the wall 23a is laterally spaced from the other side of the median plane M.

The opposite faces 22'a and 23'a of the walls 22a and 23a, respectively, comprise upwardly opening vertical bearing block guideways in the housing and supporting member 15a and the lower ends of the walls 22a and 23a merge with the upper ends of a segmental cylindric bearing mounting wall 24a extending between the walls 16a and 17a, and the upper and central portions of the wall 16a terminate and merge with edges of the walls 22a, 23a, and 24a.

The housing and supporting member 15b includes longitudinally spaced laterally and vertically extending walls 16b and 17b and laterally spaced longitudinally and vertically extending walls 18b and 19b. The walls 16b and 17b merge at their vertically extending edges with the walls 18b and 19b to form a vertically extending housing chamber 20b which is open at its lower end.

The housing and supporting member 15b also includes an upper normally horizontal wall 21—1b merging at its edges with the upper edges of the walls 16b, 18b, and 17b, and with the upper end of a normally vertical wall 22b extending longitudinally between the walls 16b and 17b, and the wall 22b is laterally spaced from one side of the median plane M.

The housing and supporting member 15b also includes an upper normally horizontal wall 21—2b merging at its edges with the upper edges of the walls 16b, 19b, and 17b, and with the upper end of a normally vertical wall 23b extending longitudinally between the walls 16b and 17b, and the wall 23b is lat-

erally spaced from the other side of the median plane M.

The opposite faces 22'b and 23'b of the walls 22b and 23b, respectively, comprise upwardly opening vertical bearing block guideways in the housing and supporting member 15b, and the lower ends of the walls 22b and 23b merge with the side edges of a guideway bottom wall 24b extending between the walls 16b and 17b, and the upper and central portions of the wall 16b terminate and merge with edges of the walls 22b, 23b, and 24b.

The wall 16a of the housing and supporting member 15a has formed therein a circular opening 25a registering with the bore of the cylindric wall 24a for separably receiving a cylindric tubular bearing member 26 extending laterally from one side of a reversing gear unit, indicated generally by 27.

The bearing member 26 extends through the circular opening 25a and is located and fits within the cylindric bore of the segmental wall 24a.

The reversing gear unit 27 includes walls 25 forming a case 28 from one side of which the bearing member 26 extends, preferably so that the outer cylindric surface 29 of the bearing member 26 is at right angles to a flat side face 30 of the case 28, beyond which face 30 the bearing member extends, and the flat side face 30 of the case 28 seats against the flat outer face 31 of the wall 16a of the housing and supporting member 15a, whereby the unit 27 may be conveniently separably connected with the wringer frame 11, as by means of cap screws 32 extending through apertures formed in flanges 33 and 33' of the case 28, the flange apertures registering with threaded apertures formed in the wall 16a.

The bearing member 26 has formed therein a cylindric bearing surface 34 which extends into a neck 35 of the case 28, and the opposite ends of the cylindric bearing surface 34 are terminated by opposite thrust faces 36 and 37 formed respectively in the neck 35 and the member 26.

A connector sleeve shaft 38 is journaled in the cylindric bearing surface 34, and the ends of the sleeve shaft 38 abut against the thrust faces 36 and 37.

A cylindric pilot bore 39 extends from the end of the sleeve shaft 38 located within the frame 11 and communicates with a polygonal bore 40 extending from the opposite end of the sleeve shaft 38, and the polygonal bore 40 is preferably a hexagonal bore as illustrated.

The normally lower roll for the wringer indicated generally by 41-1, preferably includes a cylindric thick wall tube 42-1 of resilient material, which may be rubber, fitting on and secured to a shaft 43-1 extending beyond the opposite ends of the tube 42-1.

The end 44-1a of the shaft 43-1 adjacent

the reversing gearing unit 27, terminates in a polygonal extremity 45-1a fitting in the polygonal bore 40 of the sleeve shaft 38, and the polygonal extremity 45-1a is reduced in diameter with respect to the shaft end 44-1a, which is cylindric and which fits in the pilot bore 39 of the sleeve shaft 38.

The other end 44-1b of the shaft 43-1 is reduced in diameter and is cylindric, and is journaled in the cylindric bore 46 of a novel reversing bearing block 47, which slidably fits and is maintained against rotation between the guideway faces 22'b and 23'b of the walls 22b and 23b, respectively; and the bearing block 47 for the shaft end 44-1b rests upon the upper flat face 24'b of the wall 24b of the housing and supporting member 15b.

The normally lower roll 41-1 is thus journaled in the frame 11.

The wringer 10 furthermore includes a normally upper roll indicated generally by 41-2, which includes a cylindric thick wall tube 42-2 of a resilient material, which may be rubber, fitting on and secured to a shaft 43-2 extending beyond the opposite ends of the tube 42-2.

The end 44-2a of the shaft 43-2, adjacent the unit 27, is cylindric and is journaled in the bore 46 of another of the novel bearing blocks 47, and the bearing block 47 for the shaft end 44-2a slidably fits and is maintained against rotation between the guideway faces 22'a and 23'a of the walls 22a and 23a of the housing and supporting member 15a.

The other end 44-2b of the shaft 43-2 is cylindric and is journaled in the bore 46 of still another of the bearing blocks 47, and the bearing block 47 for the shaft end 44-2b slidably fits and is maintained against rotation between the guideway faces 22'b and 23'b of the walls 22b and 23b.

Each of the novel bearing blocks 47 includes a tubular member 48 within which the bore 46 is formed, and the tubular member 48 preferably extends beyond opposite faces of the block 47.

The block 47 is rectangular, as illustrated, and includes side faces 47' and 47'', which reversibly fit and slide between the guideway faces 22'a and 23'a, or the guideway faces 22'b and 23'b.

Each block 47 also includes end faces 47''' and 47'''', one of which is uppermost in use.

As illustrated, the reversible bearing blocks 47 are so positioned that the blocks for the upper roll shaft ends 44-2a and 44-2b, have their end faces 47''' uppermost.

The wringer 10 furthermore includes a head 50, which is mounted for movement with respect to the frame, preferably by yielding pivotal means indicated generally by 51a and 51b.

The yielding pivotal means 51a and 51b

are located so that the head 50 may be swung towards and away from the upper roll 41-2 about a horizontal longitudinally extending axis 52-1 at one side of the rolls 41-1 and 5 41-2.

Means are provided on each end of the head 50 for abutment against the upper end faces of the bearing blocks 47 journaling the upper roll 41-2 for pressing the upper roll 10 41-2 against the lower roll 41-1; and in the illustrated embodiment of the invention, the head abutment means include shoulders 53a and 53b located at the opposite ends of the head 50, and adapted for abutment

- 15 41-2 against the lower roll 41-1; and in the illustrated embodiment of the invention, the head abutment means include shoulders 53a and 53b located at the opposite ends of the head 50, and adapted for abutment 15 toward and away from the upper roll 41-2 so that the normally lower faces 53'a and 53'b of the shoulders 53a and 53b respectively abut against the upper end faces of the bearing blocks 47 for the upper roll 41-2.

- 20 The head 50 is of sufficient width laterally to extend across the upper roll 41-2 from the yielding pivotal mounting of the head 50 at one side of the rolls to the other side of the rolls.

- 25 Catch means, preferably hook means 54a and 54b are located at the side of the rolls opposite to that of the yielding pivotal mounting means 51-a and 51-b, and means indicated generally by 55a and 55b, respec-

- 30 tively, yieldingly and pivotally mount the hook means 54a and 54b on the frame for swinging about a normally horizontal axis 52-2 located on the opposite side of the rolls to that of the axis 52-1 about which the head 35 50 swings.

- Hook engaging means indicated generally by 56a and 56b are movably mounted on the head 50 for selective engagement respectively with the hook means 54a and 54b, and hook displacing means 57a and 57b are movably mounted on the head 50 for positively displacing the hook means 54a and 54b for engagement thereof with the engaging means 56a and 56b.

- 45 The engaging means 56a and the displacing means 57a preferably comprise cam members extending in different directions and secured to a stub shaft 58a, which is journaled in the head 50, and similarly, the engaging means 56b and the displacing means 57b preferably comprise cam members extending in different directions and secured to a stub shaft 58b which is journaled in the head 50.

- 50 As illustrated, the engaging cam member 56a and a displacing cam member 57a are located at one end of a longitudinally and laterally extending lever 59, and the engaging cam member 56a and the displacing cam member 57a are similarly located on the other end of the lever 59.

- The hook means 54a includes a catch head 60a which extends towards the rolls for engagement by the engaging cam member 56a; and the hook means 54b is similarly arranged.

- 55 The yielding and pivoting means 55a, by

which the hook means 54a is mounted on the frame 11, includes a normally vertical shaft 61a slidably extending through a bore formed in the upper wall 21-2a of the housing and supporting member 15a.

The lower end 62a of the hook means 54a is pivotally connected with the upper end 63a of the shaft 61a, above the wall 21-2a, as by means of a pin 64a extending through suitable apertures formed in the hook means 70 lower end 62a, and in the shaft upper end 63a; and below the wall 21-2a a compression spring 65a is interposed between the lower face 21-2'a of the wall 21-2a and the upper face 66'a of a washer 66a adjustably positioned on the shaft 61a as by means of a bolt 67a screwed on the threaded lower end 68a of the shaft 61a.

The yielding and pivoting means 55b, and 80 51a and 51b are similar in detail to the means 55a.

In other words, by the construction and arrangement described in detail by the foregoing, the wringer 10 is provided with improved substantially instantaneously releasable means applying pressure between the rolls 42-1 and 42-2 of the wringer 10, and which operates as follows:

Fig. 6 illustrates the relative positions of the parts of the wringer after the head 50 95 has been swung downwardly over the upper roll 41-2, with the shoulders 53a and 53b abutting the upper bearing blocks 47, and the lever 59 rotated to its position of extreme displacement with respect to the head 50, positioning the engaging cam members 56a and 56b for being engaged by the hook means 54a and 54b, respectively; and the hook means having been sprung back and snapped over the engaging members.

100 Rotation of the lever 59 towards the head 50, to the position illustrated best in Fig. 4, serves to clamp the rolls against each other, and place the wringer in position for use.

If the rolls become clogged in use, or the operator's fingers become caught between the rolls, a single downward blow on the lever 59 serves to rotate the displacing cam members 57a and 57b against the hook means 54a and 54b, whereby the hook means are positively displaced from engagement with the members 56a and 56b, respectively, and the head 50 springs free to the position illustrated in Fig. 5, with the pressure between the rolls released.

110 The wringer 10, furthermore includes an improved automatically reversing drain board indicated generally by 160, and which includes a longitudinally extending drain board member 161 whose upper surface 161' is preferably concaved and laterally symmetrical with respect to the vertically longitudinal median plane M.

115 The drain board member 161 is located below the lower roll 42-1 and above the frame 130

base 12, and extends longitudinally between the frame end members 15a and 15b.

Means are provided for mounting the drain board member 161 for pivoting about a normally horizontal longitudinally extending axis located in the plane M, and the pivotal mounting means for the drain board member 161 may include pivot lugs 162a and 162b depending from opposite ends of the drain board member 161, and pivotally seating respectively in grooves 163a and 163b which are formed in the upper surface 12' of the frame base member 12.

Preferably split collar means 164 are located on the cylindric end 44-1a of the shaft 43-1 between the adjacent end of the rubber tube 42-1 and the opposite end of the bearing member 26.

A plurality of radially extending friction plugs 165 are interposed between the split collar 164 and the shaft end 44-1a, and adjustable bolt means 166 are provided for applying a variable tension on the outer ends 164a and 164b of the preferably hinged split collar 164, thereby maintaining the frictional pressure between the shaft end 44-1a and the friction plugs 165, which are preferably seated in inwardly opening sockets formed in the inner surface of the split collar 164.

The collar 164 is operatively connected with the drain board member 161, as by means of circumferentially spaced teeth 167a and 167b extending outwardly from one side of the collar 164, and receiving therebetween the upper end 168 of an arm 169 secured to and extending upwardly from the drain board member 161.

Accordingly, when the rolls are rotating in the direction indicated by the arrows 70-1 and 70-2 in Fig. 7, the drain board member 161 will be swung to one side to the position illustrated in Fig. 7, in which one side 161a of the drain board member 161 is abutting against the upper surface 12' of the frame base 12 on one side of the rolls, and the frictional pressure between the collar 164 and the shaft 41-1a is such that the rolls then continuously rotate in the direction of the arrows 70-1 and 70-2 by slipping of the shaft end 44-1a across the abutting ends of the friction plugs 165.

When, however, the direction of rotation of the rolls is reversed, the frictional pressure on the plugs 165 is sufficient to swing the collar 164 in the opposite direction until the other side 161b of the drain board member 161 strikes against the upper surface 12' of the base 12 on the other side of the rolls, whereby the drain board member 161 is automatically reversed to always slope downwardly below the lower roll 42-1 in the direction of rotation thereof.

For strengthening the frame 11 and at the same time forming on opposite sides of the rolls, drain troughs extending beyond the

sides of the drain board member 161, the frame 11 is preferably provided with webs 71-1a and 71-1b extending respectively between one side of the frame end member 15a and the base 12, and between one side of the frame end member 15b and the base 12.

Similarly, webs 71-2a and 71-2b extend respectively between the other side of the frame end member 15a and the base 12, and between the other side of the frame end member 15b and the base 12.

The wringer 10 furthermore preferably includes formed metal feed boards 72-1 and 72-2 located on opposite sides of the rolls.

The feed board 72-1 is located on one side of the rolls, and includes hanger pins 73-1a and 73-1b extending respectively from opposite ends of the feed board, and the pin 73-1a is removably supported at the base of an upwardly opening slotted shoulder 74-1a which is formed in the upper end of the frame end member 15a; and the pin 73-1b is similarly removably supported at the base of an upwardly opening slotted shoulder formed in the upper end of the frame end member 15b.

The other feed board 72-2 is similarly constructed and removably supported at the other side of the rolls.

I claim:

1. In wringing apparatus and the like, a frame, a head, means mounting the head for movement with respect to the frame, pressure means interposed and reacting between the head and the frame, a hook, means mounting the hook on the frame for movement laterally with respect to the frame, hook engaging means movably mounted on the head for selectively engaging the hook, and means movably mounted on the head and operable for positively displacing the hook from the engaging means.

2. In wringing apparatus and the like, a frame, a head, means mounting the head for movement with respect to the frame, pressure means interposed and reacting between the head and the frame, catch means, means mounting the catch means on the frame for movement laterally with respect to the frame, catch engaging means movably mounted on the head for selectively engaging the catch means, and means movably mounted on the head and operable for positively displacing the catch means from the engaging means.

3. In wringing apparatus and the like, a frame, a head, yielding means mounting the head for movement with respect to the frame, pressure means interposed and reacting between the head and the frame, catch means, yielding means mounting the catch means on the frame for movement laterally with respect to the frame, catch engaging means movably mounted on the head for selectively engaging the catch means, and means movably mounted on the head and operable for

positively displacing the catch means from the engaging means.

4. In wringing apparatus and the like, a frame, a head pivotally mounted on the frame, pressure means interposed and reacting between the head and the frame, catch means, means pivotally mounting the catch means on the frame, a shaft operatively mounted for rotation on the head, catch engaging means mounted on the shaft for selectively engaging the catch means by rotation of the shaft, and means mounted on the shaft for positively displacing the catch means from the engaging means by further rotation of the shaft.

5. In wringing apparatus and the like, a frame, a head, yielding means pivotally mounting the head on the frame, pressure means interposed and reacting between the head and the frame, catch means, yielding means pivotally mounting the catch means on the frame, a shaft operatively mounted for rotation on the head, catch engaging means mounted on the shaft for selectively engaging the catch means by rotation of the shaft, and means mounted on the shaft for positively displacing the catch means from the engaging means by further rotation of the shaft.

6. Apparatus, for use as a wringer and the like, including a frame, a normally lower roll, a normally upper roll, means journaling the lower roll in the frame, bearing blocks journaling the upper roll, means mounting the bearing blocks in the frame for sliding towards and away from the lower roll, a head, means located at one side of the rolls and pivotally mounting the head on the frame, means on the head adapted for abutment against the upper roll bearing blocks for pressing the upper roll against the lower roll, catch means, means located at the other side of the rolls and pivotally mounting the catch means on the frame, a shaft operatively mounted for rotation on the head, catch engaging means mounted on the shaft for selectively engaging the catch means by rotation of the shaft for applying pressure between the rolls, and means mounted on the shaft for positively displacing the catch means from the engaging means by further rotation of the shaft.

7. Apparatus, for use as a wringer and the like, including a frame, a normally lower roll, a normally upper roll, means journaling the lower roll in the frame, bearing blocks journaling the upper roll, means mounting the bearing blocks in the frame for sliding towards and away from the lower roll, a head, yielding means located at one side of the rolls and pivotally mounting the head on the frame, means on the head adapted for abutment against the upper roll bearing blocks for pressing the upper roll against the lower roll, catch means, yielding means lo-

cated at the other side of the rolls and pivotally mounting the catch means on the frame, a shaft operatively mounted for rotation on the head, catch engaging means mounted on the shaft for selectively engaging the catch means by rotation of the shaft for applying pressure between the rolls, and means mounted on the shaft for positively displacing the catch means from the engaging means by further rotation of the shaft.

8. In wringing apparatus and the like, a frame including a base member, the upper surface of said base member having grooves formed therein, normally upper and lower rolls operatively mounted in the frame, a drain board member, lugs depending from the drain board member and pivotally seated in said grooves for pivotally mounting said drain board member on the frame below the lower roll, the lower roll including a shaft, means frictionally mounted on the shaft, and means operatively connecting the frictionally mounted means with the drain board member whereby the inclination of the drain board is automatically reversed when the direction of rotation of the rolls is reversed.

9. In wringing apparatus and the like, a frame, normally upper and lower rolls operatively mounted in the frame, a drain board member pivotally mounted on the frame below the lower roll, the lower roll including a shaft, collar means about the shaft, a plurality of radially extending friction plugs interposed between the collar and the shaft, and means operatively connecting the collar means with the drain board member whereby the inclination of the drain board member is automatically reversed when the direction of the rotation of the rolls is reversed.

In testimony that I claim the above, I have hereunto subscribed my name.
